MAGAZINE CLOSURE FOR STAPLING MACHINES

Oscar A. Wandel, Chicago, Ill., assignor to
Henry A. Torstenson, Chicago, Ill.

Application July 10, 1947, Serial No. 760,059

5 Claims. (Cl. 1—49)

1

This invention is concerned with improvements in a portable tacker or fastener driving device which is adapted to drive a U-shaped staple into a surface of wood, cardboard or similar material.

More particularly, the invention is concerned with a fastener driving device of the type which comprises a forward chamber having a vertical fastener guideway therein, a reciprocal driving plunger in the driveway, a bottom horizontally disposed fastener feeding chamber provided with means for delivering fasteners to driving position beneath the plunger and a plunger actuating mechanism which is operated by a pivotal rearwardly directed handle member. In this type of fastener driving device, clogging sometimes occurs in the narrow guideway through which the staples are driven due to one or more of the staples being too large or too small or of incorrect form. To permit the guideway to be cleared when this occurs a section of the front wall of the guideway is made removable.

An object of the present invention is to provide in a fastener driving device of the type described, an improved mechanism for effecting quick and easy release of a removable section of the front wall of the fastener guideway and accurate, quick and easy replacement of the same.

Another object of the invention is to provide a fastener device of the type described having a movable front wall section in combination with mounting means therefor which permits the section to be readily and easily moved to expose the end of the fastener guideway without disconnecting the section from the device and which insures rapid and accurate restoring of the section to guideway forming position.

Other objects and advantages of the invention will be apparent to those skilled in the art from a description of the preferred form thereof which is shown by way of illustration in the accompanying drawings, wherein:

Fig. 1 is a perspective view of a fastener driving device embodying the principles of the invention;

Fig. 2 is a side elevation of the device to an enlarged scale;

Fig. 3 is a partial vertical section through the front wall of the device;

Fig. 4 is a perspective view of the removable

2

front wall section of the guideway and its securing mechanism; and

Fig. 5 is a transverse section taken on line 5—5 of Fig. 2.

5 The present invention is applicable to all kinds of fastener driving devices, such as stapling machines, compression tackers, magazine hammers, etc. Only one application thereof has been illustrated. For convenience the invention is shown 10 embodied in a tacker used for driving U-shaped staples into wood, cardboard or other surfaces.

A tacker of this type is shown and described in the copending application of Kenneth F. Morberg, Serial No. 717,692, filed December 20, 1946, 15 issued as U. S. Letters Patent No. 2,456,526, on December 14, 1948, to which reference is made for a detailed description of those features which are not described in detail in this application.

The tacker comprises a generally U-shaped 20 frame 10 having a forward chamber or driving head 11 formed by the spaced vertical frame side plates 12 and 13. The forward ends of the side plates 12 and 13 are turned inwardly at 14 and 15 and form part of the front face of the tacker and the forward side of a guideway for the driving plunger 16 which is vertically reciprocal in the guideway.

The driving plunger 16 is reciprocally mounted on a fixed guide post 17 and is actuated by a compression spring 18 which surrounds the post 17 30 with its lower end seated in a recess 19 in the top of the plunger 16 and which extends to the cap 20 at the top of the guideway. The plunger 16 carries a staple driving blade 21 which is secured by a rivet 22 to the forward face thereof.

The driving plunger 16 is elevated to compress the spring 18 and then released for the driving stroke by pivotal operation of a lever or handle 23 and a trip mechanism (not shown) within the 40 driving head 11 which cooperates therewith.

A bumper block 24 is secured immediately beneath the driving plunger 16 and is provided with a recess 25 receiving the lower end of the guide post 17 and a shock-absorbing bumper spring 26 45 which is engaged by the lower end of the driving plunger 16 to cushion the shock at the end of the driving stroke.

A staple supply and delivery mechanism 27 is arranged beneath the bumper block 24 in the horizontal chamber or magazine 28 formed by the

side frame members 12, 13 and the bottom frame member 29. The chamber 28 extends rearwardly from the driving head 11 and the staple delivery mechanism 27 is removable at the rear to re-load the device with a supply of the staples 30.

The front flanges 14 and 15 of the side plates 12 and 13 are cut away at their lower portions terminating at 31 and 32. A removable front wall section or member 33 forms the lower front portion of the guideway for the staple driving blade 21. The member 33 includes rearwardly extending side arms or flanges 34 and 35 which are adapted to embrace the lower portions of the side walls 12 and 13 of the head 11. The arms 34 and 35 are provided in their upper portions with rearwardly opening notches 36, 37 for receiving the projecting ends of the pin 38 which extends transversely of the head 11 and the ends of which form projecting indexing studs for co-operation with the notches to properly position the member 33 on the head 11.

The front wall section 33 is provided with an aperture 39 in its forward face which is in alignment with the staple feeding chamber 28. The aperture 39 will frequently permit the removal of a jammed staple without removal of the member 33. This feature of the illustrated device does not constitute part of the invention but is the subject matter of the co-pending application of Kenneth F. Morberg, Serial No. 717,691, filed Dec. 20, 1946.

The front wall section 33 is permanently connected to the device by link members 40, 41 and the pivotally mounted yoke member 44. The link members 40 and 41 are pivotally connected at 42 and 43 to the rearwardly extending arms 34 and 35 of the member 33 adjacent the lower edge thereof and extend rearwardly therefrom to the rear edge of the yoke member 44 being pivotally connected thereto at 45, 46. The yoke member 44 is generally U-shaped with legs 47 and 48 extending downwardly and embracing the side walls of the magazine forming portion 49 of the frame 10. The legs 47 and 48 are pivotally connected at 50 and 51 to the frame portion 49, the pivot points 50 and 51 being spaced forwardly of the pivotal connections 45 and 46 and slightly above a line connecting the pivot points 42, 45 and 43, 46, respectively. The yoke member 44 is provided with a rearwardly extending bight portion having laterally extending ends 52 and 53 by means of which it may be gripped by the fingers of the operator to pivot the yoke about the pivot points 50 and 51.

As illustrated in dotted line in Fig. 2, when the operating yoke member 44 is raised or pivoted counterclockwise about the pivot points 50 and 51 the links 40 and 41 force the front wall section 33 forwardly and disengage the indexing studs from the notches 36 and 37, permitting the member 33 to swing downwardly away from the front of the head 11 about the pivot points 45 and 46, thus exposing the entire forward end of the staple driving guideway and permitting removal of any jammed staples which cannot be readily moved through the aperture 39.

The member 33 is restored to closing position on the head 11 by moving the same upwardly and rearwardly to reengage the ends of the pin 38 in the slots 36 and 37 while the yoke 44 is pivoted clockwise about pivot points 50 and 51 until it is fully seated on the frame portion 49, the pivot points being so related that the member 33 is thereby retained in closed position on the head 11.

While specific details of construction have been referred to in describing the illustrated device, it will be understood that other details of construction may be resorted to within the spirit of the invention.

I claim:

1. In a fastener driving device comprising a head having a vertical fastener driveway and a staple driving blade operable in said guideway, a movable front wall section for said guideway provided with flanges which extend rearwardly in engagement with the side walls of the head, said flanges being provided with rearwardly opening notches, indexing studs which project laterally of the side walls of the head into the rearwardly opening notches in the flanges for positioning the flanges accurately when the same are moved into their rearmost positions, and means for positively locking the flanges in their rearmost position including a pair of pivotally connected link elements pivoted to one of said flanges and to said side walls.

2. In a fastener driving device comprising a head having a vertical fastener driveway and a staple driving blade operable in said guideway, a movable front wall section for said guideway provided with flanges which extend rearwardly in engagement with the side walls of the head, said flanges being provided with rearwardly opening notches, indexing studs which project laterally of the side walls of the head into the rearwardly opening notches in the flanges for positioning the flanges accurately when the same are moved into their rearmost positions, and means including swingable link members pivotally connecting said flanges with the side walls of said device.

3. In a fastener driving device comprising a frame having a forward chamber provided with a vertical fastener guideway and a fastener driving blade in said guideway, a separable front wall section closing a portion of said guideway, means for guiding said section to and from closed position on said frame, and connecting means cooperating with said guide means for moving said section, said connecting means comprising a strap member pivoted to said frame and a link pivoted to said strap member and to said wall section.

4. In a fastener driving device comprising a frame having a forward chamber provided with a vertical fastener guideway and a fastener driving blade in said guideway, a separable front wall section closing a portion of said guideway adjacent the bottom of said chamber, said front wall section having rearwardly extending side arm members embracing the forward sides of said frame, said side arm members being provided with rearwardly opening slots, laterally extending pins on said frame adapted to be received in said slots when said front wall section is in closing position, a pair of link members each having one end pivoted to one of said side arm members at a point below said slots, an operating means for said links pivotally connected to said links and to said frame whereby in one position of said strap member said wall section is held in closed position and in another position of said strap member said wall section is moved to expose said guideway.

5. In a fastener driving device comprising a frame having a forward chamber provided with a vertical fastener guideway and a fastener driving blade in said guideway, a separable front wall section closing a portion of said guideway adjacent the bottom of said chamber, said front

wall section having rearwardly extending side arm members embracing the forward sides of said frame, said side arm members being provided with rearwardly opening slots, laterally extending pins on said frame adapted to be received in said slots when said front wall section is in closing position, a pair of link members each having one end pivoted to one of said side arm members at a point below said slots, a U-shaped strap member having leg portions pivoted at the ends thereof to said frame rearwardly of said side arm members and straddling a portion

10

of said frame, said link members being pivoted at their other ends to the legs of said strap member rearwardly of said pivotal connection with said frame whereby in one position of said strap member said wall section is held in closed position and in another position of said strap member said wall section is moved to expose said guideway.
